ARVID H. NERO, OF NEW BRITAIN, CONNECTICUT, ASSIGNOR TO THE ARROW ELECTRIC COMPANY, OF HARTFORD, CONNECTICUT, A CORPORATION OF CONNECTICUT.

ATTACHMENT-PLUG RECEPTACLE.

Application filed June 9, 1921. Serial No. 476,263.

My invention relates to attachment plug receptacles, and particularly to the construction and support of the jack-receiving terminals, and the associated construction of 5 the insulating body of the receptacle and its support.

In the accompanying drawings—

Fig. 1 is a plan of a receptacle in which my invention is embodied in one form;

10 Fig. 2 is a longitudinal section on the line 2—2, Fig. 1;

Fig. 3 is a broken inverted plan of a receptacle;

15 Fig. 4 is a plan view of a blank from which one of the terminals is formed; and

Fig. 5 is a perspective of one of the terminals detached.

In the form shown in Figs. 1 to 5, the present receptacle comprises a one-piece insulating base 10 provided with a circular up- 20 standing boss 11 which is accommodated in a circular recess in the face plate 12 and is provided, as usual, with suitable T-shaped apertures 13 and 14 for the admission of 25 the jack blades of a cooperating plug (not shown) which engage the receptacle terminals hereinafter described. The insulating base is laterally channelled at 15 and 16 to accommodate the leading-in wires, respectively connected to the binding screw terminals 17 and 18 which rest on depressed ledges 19 and 20 respectively. Supporting lugs 21 and 22, by which the receptacle may be mounted in the customary fashion in the 30 outlet box (not shown), rest in depressions 23 and 24 at opposite ends of the receptacle and are engaged by screw bolts 25 and 26 which pierce the base.

The receptacle terminals, which are identical in form, are illustrated in detail in Figs. 4 and 5. As indicated, each terminal is formed from a single blank and comprises a connection strap 27 pierced at 28 to receive the screw bolt 29 which passes there- 40 through and takes into one or the other of the binding screw terminals 18 or 19, thus establishing electrical connection between these parts, as well as mechanically securing the same in position on the base. Each 45 terminal also comprises brushes 30, 31, and 32, lying at right angles to each other in

the blank (Fig. 4). The brush 32 has a wing 33 which, in the finished terminal, is offset at right angles to the plane of the brush 32, so that when the several brushes 55 are formed up into a completed terminal, the brushes 30 and 32 are opposed on the one hand, while the brush 31 and the wing 33 are opposed on the other hand but lie in a plane at right angles to that of the first- 60 mentioned pair. When the contact is properly located in its recess 34, let into the lower face of the base, the brushes 30 and 32 for the respective terminals receive a jack blade passing through the head of the T- 65 slot 13 or 14, while the brushes 31 and brush wing 33 receive the jack blade passing through the stem of the T-slot. The receptacle contacts are thus designed to accommodate plug jacks arranged either in tandem 70 or parallel, or at right angles to each other. Moreover, by making the T-slot 14 of less size than the T-slot 13 the receptacle is polarized. It may be pointed out that in whichever position the jack blade enters 75 the receptacle, it contacts on one face with either the brush 30 or the brush 31, and on the other face with either the brush 32 or the wing 33. In both positions, therefore, a good wiping contact with both faces of the 80 jack blade is secured, and an excellent electrical connection therewith obtained.

A lug 35 in extension of the strap 27 is accommodated in a shallow recess 36 in the base 10 and properly locates the terminal 85 with respect to the T-slot apertures 13 and 14 in the base. It also serves to detain the receptacle contacts in position against the outward drag of the jack blades on the withdrawal of the plug.

In order to support the terminals in their respective wells 34, I provide a metal plate 37 underlying both receptacle terminals, but insulated therefrom by an interposed sheet 38 of insulation, such as fiber, mica, or the like, upon which the terminals rest. The screws 25 and 26 pass through opposite ends of the plate and support it in position.

This construction has the additional advantage that the screws 25 and 26 are definitely located a predetermined distance apart, regardless of variations in length of the

porcelain 10, and the supporting lugs 21 and 22 are therefore spaced apart a precise distance, which may be exactly predetermined with respect to the supporting lugs 5 of the outlet box and the holes for the face plate screws.

Various modifications of construction will readily occur to those dealing with the problem without departing from my underlying thought, which is to provide a receptacle of economical construction, in which the central exposed boss 11 is maintained free from other perforations than are required for the accommodation of the plug jacks; 10 second, to provide improved one-piece terminals; third, to provide underlying supports for the terminals, and preferably a single supporting plate insulated from the terminals. As will be noted in the construction shown in Figs. 1 to 5, only two screws are required at each end of the receptacle, one for connection with the binding screw terminals, and the other engaging the holding lug and supporting plate, thus 20 economizing not only in the material but in the labor of assembly. It may be pointed out that the particular terminal construction shown in Figs. 4 and 5 may be readily adapted to attachment plug receptacles of other 30 types, such for instance as separable attachment plugs, and I do not limit my invention of this feature to a flush receptacle of the type shown.

I claim:—

35 1. An attachment plug receptacle comprising a one-piece insulating body recessed from its lower face to afford a plurality of contact chambers and apertured in its outer face to form blade-guide passages opening to said contact chambers, jack-receiving contacts of opposite polarity respectively housed within said chambers in register with said guide passages, in combination with insulating sheet material underlying said contacts of 45 opposite polarity, and a sheet metal plate secured to the body and underlying said insulating sheet material and cooperating with the latter to support said contacts in said chambers together with receptacle mounting means 50 metallically connected with said underlying plate.

55 2. An attachment plug receptacle comprising a one-piece insulating body recessed from its lower face to afford a plurality of contact chambers and apertured in its outer face to form blade-guide passages opening to said contact chambers, jack-receiving contacts of opposite polarity respectively housed within said chambers in register with said guide passages, in combination with insulating sheet material underlying said contacts of 60 opposite polarity, and a sheet metal plate secured to the body and underlying said insulating sheet material and cooperating with the latter to support said contacts in said 65

chambers, the lower face of the body being recessed to accommodate said sheet metal plate and insulating sheet material together with receptacle mounting means 70 metallically connected with said underlying plate.

3. An attachment plug receptacle comprising a one-piece insulating body recessed from its lower face to afford a plurality of contact chambers and apertured in its outer face to form blade-guide passages opening 75 to said contact chambers, jack-receiving contacts of opposite polarity respectively housed within said chambers in register with said guide passages, in combination with insulating sheet material underlying said contacts of opposite polarity, and a sheet metal plate secured to the body and underlying said insulating sheet material and cooperating with the latter to support said contacts in said chambers, said sheet metal plate and insulating sheet material being confined within the boundaries of the lower face of the base together with receptacle mounting means 80 metallically connected with said underlying plate.

4. An attachment plug receptacle comprising a one-piece insulating body recessed from its lower face to afford a plurality of contact chambers and apertures in its outer face to form blade-guide passages opening to 90 said contact chambers, jack-receiving contacts of opposite polarity respectively housed within said chambers in register with said guide passages, in combination with insulating sheet material underlying said contacts of opposite polarity, and a sheet metal plate secured to the body and underlying said insulating sheet material and cooperating with the latter to support said contacts in said chambers, and receptacle supporting lugs 95 engaged by the means which secure the sheet metal plate to the insulating body.

5. An attachment plug receptacle comprising a one-piece insulating body recessed from its lower face to afford a plurality of contact chambers and apertured in its outer face to form blade-guide passages opening to 110 said contact chambers, jack-receiving contacts of opposite polarity respectively housed within said chambers in register with said guide passages, in combination with insulating sheet material underlying said contacts of opposite polarity, and a sheet metal plate secured to the body and underlying said insulating sheet material and cooperating with the latter to support said contacts in said chambers, said insulating sheet material and sheet metal plate being substantially coextensive together with receptacle mounting means 115 metallically connected with said underlying plate.

6. An attachment plug receptacle comprising a one-piece insulating body recessed from its lower face to afford a plurality of contact chambers and apertured in its outer 120

face to form blade-guide passages opening to said contact chambers, jack-receiving contacts of opposite polarity respectively housed within said chambers in register with said guide passages, in combination with insulating sheet material underlying said contacts of opposite polarity, and a sheet metal plate secured to the body and underlying said insulating sheet material and cooperating with the latter to support said contacts in said chambers, said contacts having laterally extending base members pressed against the base by said supporting members beyond the boundaries of the contact chambers together with receptacle mounting means metallically connected with said underlying plate.

7. An attachment plug receptacle comprising a one-piece insulating body recessed from its lower face to afford a plurality of contact chambers and apertured in its outer face to form blade-guide passages opening to said contact chambers, jack-receiving contacts of opposite polarity respectively housed within said chambers in register with said guide passages, in combination with insulating sheet material underlying said contacts of opposite polarity, and a sheet metal plate secured to the body and underlying said insulating sheet material and cooperating with the latter to support said contacts in said chambers, each of said contacts having base members extending on different sides of its contact chamber and pressed against the lower face of the base by said supporting members together with receptacle mounting means metallically connected with said underlying plate.

8. An attachment plug receptacle comprising a one-piece insulating body recessed in its lower face to afford a pair of contact-receiving chambers and apertured in its upper face in register with said recesses to afford blade guide passageways, a pair of jack-receiving contacts of opposite polarity housed within the said recesses, and in register with the blade guide apertures, a supporting plate underlying said contacts and common thereto, means for insulating said plate from said contacts, and means for securing said plate to said body in contact-supporting position, together with receptacle mounting means metallically connected to said plate-securing means.

9. In an attachment plug receptacle, a molded insulating body recessed from its lower face to afford a contact chamber, and a one-piece contact entering said chamber from the lower face of the body, the base of said contact having a laterally extending integral branch for electrical connection with a source of current and an integral lug extending in another direction from said base and underlying the receptacle body to detain the contact against outward displace-

ment under the frictional drag of a co-operating jack blade on withdrawal of the latter.

10. A push plug receptacle comprising a one-piece molded insulating body recessed from its lower face to accommodate contacts, contacts of opposite polarity insertable from said lower face into the recessed body and having laterally extending base elements resting against the lower face of the body, wire terminals associated with said base elements of the contacts and accommodated by said body, sheet insulation underlying the contacts and their base elements to support and house the same, means for securing said sheet insulation to the body, together with mounting means at opposite ends of the body for securing the same to a suitable support.

11. A push plug receptacle comprising a one-piece molded insulating body recessed from its lower face to accommodate contacts, contacts of opposite polarity insertable from said lower face into the recessed body and having laterally extending base elements resting against the lower face of the body, wire terminals associated with said base elements of the contacts and accommodated by said body, a punched metal plate underlying the contacts and their base elements, sheet insulation interposed between said plate and the contact elements, means for securing the plate and sheet insulation to the body, together with mounting means at opposite ends of the body for securing the same in a suitable support.

12. An attachment plug receptacle comprising a molded insulating body recessed from its lower face to accommodate contacts, contacts insertable from said lower face into the recessed body and having laterally extending base elements, sheet insulation underlying said contacts and their laterally extending base elements to support the same, receptacle mounting means at the face of the receptacle, and means common to said receptacle mounting means and sheet insulation for securing the same to the receptacle body.

13. An attachment plug receptacle comprising a molded insulating body recessed from its lower face to accommodate contacts, contacts insertable from said lower face into the recessed body and having laterally extending base elements, sheet insulation underlying said contacts and their laterally extending base elements to support the same, a punched metal member beneath and reinforcing said sheet insulation, receptacle mounting means metallically connected to said punched metal member, said punched metal member being secured to the insulating base to support the sheet insulation and receptacle contacts in position.

14. In an attachment plug receptacle de-

vice, a one-piece contact having two brushes lying substantially at right angles to each other, in combination with a cooperating brush member having brush portions offset at right angles to each other to respectively face the first-mentioned brushes.

15. In an attachment plug receptacle device, a contact comprising brushes lying at

right angles to each other, and a cooperating brush having portions offset at right angles ¹⁰ to each other to face respectively the first-mentioned brushes.

In testimony whereof I have signed my name to this specification.

ARVID H. NERO.
